(57) **CLAIM**

The ornamental design for the extruded slatwall section, as shown and described.

DESCRIPTION

FIG. 1 depicts a front isometric view of an extruded slatwall section design;

FIG. 2 depicts a side view of the design;

FIG. 3 depicts a front view of the design;

FIG. 4 depicts a back view of the design;

FIG. 5 depicts a bottom view of the design;

FIG. 6 depicts a top view of the design;

FIG. 7 depicts a front view of a second embodiment of the design with a wood grain surface pattern on the front face; and,

FIG. 8 depicts a front view of a third embodiment of the design with a stucco surface pattern on the front face.

The extruded slatwall section has been broken in the center to indicate indefinite length.
